UNITED STATES PATENT OFFICE.

GEORGE MILBANK, OF CHILlicothe, MISSOURI.

MEANS FOR ADJUSTING AND SUPPORTING MILLSTONES, &c.

SPECIFICATION forming part of Letters Patent No. 275,929, dated April 17, 1883.

Application filed February 28, 1882. (No model.)

To all whom it may concern:

Be it known that I, GEORGE MILBANK, of Chillicothe, Livingston county, and State of Missouri, have invented new and useful Means 5 for Adjusting and Supporting Millstones, &c., of which the following is a specification.

This invention can be stated to relate to improved means for adjusting and supporting millstones or similar disk or disks with relation to their shaft or spindle.

The main objects of this invention are, first, by the means hereinafter to be described, to adjust and support millstones so that their grinding-faces shall be parallel to each other, 15 and at the same time at right angles to their spindle; second, to retain the said right-angle parallel relation between the stones and spindle, no matter what position the latter may assume. My invention therefore is designed to 20 prevent and guard against that unequal grinding action which takes place when the bed-stone and runner are caused to grind finer on one side than the other, and to achieve a uniform and perfect grinding action, and consequent result of improved product. I attain 25 the said objects by the mechanism illustrated in the accompanying drawings, in which—

Figure 1 is a central sectional elevation of my improved machine. Fig. 2 is a top plan. 30 Fig. 3 is an inverted plan of the mill above the plane of line xx of Fig. 1; Fig. 4, a top plan of upper stone and the parts connecting it to the spindle. Fig. 5 is a section of the upper stone, showing a plan view of its universal 35 gimbal-connection to the spindle; and Fig. 6 is a cross-section taken on line $x'x'$ of Fig. 1.

A represents the timbers constituting the usual frame, upon which the operating parts are mounted. B is the bed-stone. C is the 40 upper stone or runner. C' is the spindle. This, as shown, passes through the eye or center of both stones, the bed-stone having the journal-bearing, while the lower end of the spindle rests in a step, d, in manner as usual. As 45 here illustrated the bed-stone is stationary and the upper stone is capable of revolving with the spindle; but by having toe and step at the other end of the spindle this arrangement can be reversed and the upper stone made stationary and the lower stone to revolve with the spindle, and the same adjusting devices, here-

inafter to be described, may be used. I employ that mechanical device which is properly known as "gimbals" for supporting and connecting the bed-stone to the frame A, and a 55 like gimbal-connection to support and connect the runner to the spindle. In both instances the said gimbal-connection consists of similarly-constructed parts, as follows: a circular ring, b, in the case of the bed-stone passes 60 movably around its periphery, and has four equidistant journals or journal-bearings on its circumference. Thus the bed-stone has two journals or journal-bearings, $b' b^2$, opposite each other to engage in two of the journals or 65 journal-bearings in the ring b , and the other two journals or journal-bearings, $b^3 b^4$, in the ring b engage in like journals or bearings attached to the frame A. (See Figs. 1 and 2.) The bed-stone, therefore, by its universal gimbal-connection can oscillate in any direction in order to be made to assume, first, a correct position with the spindle, and, second, to retain 70 said position by following up any change of position on part of the spindle, as will herein- 75 after appear.

The upper universal gimbal-connection consists of the like circular ring, c, with its journals or journal-bearings fixed movably in the eye of the stone or disk between the spindle 80 and disk, and is attached to spindle by two of its journals or bearings, $c' c^2$, resting on two like journals or bearings fixed to the spindle, while the disk rests on the ring c by two journals or bearings, $c^3 c^4$, fixed to it in the eye, and 85 engaging the other two of the journals or bearings of the ring. (See Figs. 1 and 5.) Hence the upper stone or disk can also oscillate freely in all directions in order to enable the operator to adjust and correctly position the runner- 90 stone with the spindle, and also follow up with the bed-stone any change of position that the spindle may be forced to assume. The employment of the universal gimbal-connection in connection with millstones I do not claim, 95 broadly; but my invention consists in the combination with said parts of the further mechanism now to be described.

D D represent adjusting-arms, having their upper ends bolted to the under side of the bed-stone. (See Figs. 1 and 3.) The lower ends of the said arms support a sleeve or follower, d' ,

which surrounds the spindle and freely permits the same to revolve. (See Figs. 1 and 6.) d^2 are set-screws passing through threaded holes in the lower ends of the arms D, in order 5 to impinge against the outside of the follower d' in the act of lateral adjustment of the arms. (See Figs. 1 and 6.) Wedges can be substituted for the set-screws, however.

Since the universal gimbal-connection affords the bed-stone freedom of motion, it is apparent that by tightening or loosening the lower set-screws or wedges the operator can raise or lower any side of the stone or adjust it to a correct position—viz., at a right angle 5 to its spindle—and this done secure the stone in said position. The spindle can freely revolve without disturbing the set position of the bed-stone; but as soon as the spindle is shifted to one side (which frequently occurs by a pull 5) on part of the belt or other causes) the bed-stone is forced to follow up said movement and the relation of the parts is maintained. The upper stone is likewise provided with a device to adjustably secure the stone, so that its face shall be retained parallel to that of the bed-stone and at a right angle to the spindle. For 5 said purpose I provide the upper stone or disk with a spider, E, consisting of an inner and an outer circular plate, e e' , joined by radial arms e^2 , as shown in Figs. 1 and 4. By the outer circular plate the spider E is fastened to the eye of the stone. By its inner circular plate the said spider rests upon a sleeve, e^3 , which in turn is slipped on the upper end of the spindle 5 and rests upon its annular shoulder, as shown. (See Figs. 1, 2, 4.)

f represents one or more set-screws, which pass through the threaded holes of the inner circular plate, and engage the outer annular surface of the sleeve. (See Figs. 1 and 4.) Here, also, wedges can be substituted for set-screws. By tightening or loosening the set-screws or wedges f the adjustment and required position of the upper stone can be had and maintained.

The use of the sleeve e^3 prevents the necessity 45 of disengaging the set-screws, and the spider, if need be, can be lifted from the spindle and replaced again without readjusting the set-screws. When both stones are properly adjusted and secured to be at a perfect right angle to the vertical condition of their shaft or spindle, the upper stone (in operation) freely revolves with the spindle, the lower one remaining stationary. In case any change of 55 position on the part of the spindle occurs—say, its lower end is caused to shift to one side or the other—then both stones or disks move together at the same time and in the same direction with the said moving spindle. Consequently the faces of the stones or disks still 60 remain parallel with each other, and the right-angle relation between the said parts remain the same. In case of wear on one part of the step, or its being tipped to one side, or a sudden pull on the spindle takes place—in 65 short, no matter to what position the spindle is made to assume—the stones or disks will retain their said set position, so as to run in train, and grind the same on one side as on the other. 70

What I claim is—

1. In combination with the spindle C', the upper disk, C, having the supporting-gimbals, the spider E, sleeve e^3 , and adjusting-screws, as described. 75

2. In combination with a bed-stone provided with gimbals and a spindle, C', the adjusting-arms D, set-screws d^2 , and sleeve d' , as described.

3. In combination with the spindle C', the 80 bed-stone provided with gimbals and the adjusting-arms D, and the upper stone, C', provided with gimbals and the adjusting-spider E, as shown.

GEORGE MILBANK.
